THE NORRIS PETERS CO., PHOTO-LITHO., WASHINGTON, D. C.

UNITED STATES PATENT OFFICE.

FOSTER L. HARMON, OF NIOTA, TENNESSEE.

AUTOMATIC RAILWAY-SWITCH.

1,192,892.

Specification of Letters Patent. Patented Aug. 1, 1916.

Application filed June 16, 1914. Serial No. 845,472.

To all whom it may concern:

Be it known that I, FOSTER L. HARMON, a citizen of the United States, residing at Niota, in the county of McMinn, State of Tennessee, have invented certain new and useful Improvements in Automatic Railway-Switches; and I do hereby declare the following to be a full, clear, and exact description of the invention, such as will enable others skilled in the art to which it app pertains to make and use the same.

This invention relates to improvements in railway switches, and particularly to automatic railway switches.

15 The principal object of the invention is to provide a railway switch of such construction and arrangement that danger of a train being derailed by running over an open switch, is reduced to a minimum.

20 Another object is to provide a switch operating mechanism and train actuated means for opening and closing the switch, hand operating means for accomplishing the same result, and means for preventing direct 25 manual actuation of the train actuated means.

Other objects and advantages will be apparent from the following description, when taken in connection with the accompanying 30 drawings.

In the drawings: Figure 1 is a plan view of portions of a railway track and switch together with the train and manual means for operating the switch. Fig. 2 is a vertical 35 longitudinal sectional view on the line 2—2 of Fig. 1. Fig. 3 is a vertical transverse sectional view on the line 3—3 of Fig. 1. Fig. 4 is a side elevation of one of the train actuated means. Fig. 5 is a plan view of the 40 switch set in position for the curve. Fig. 6 is a horizontal sectional view on the line 6—6 of Fig. 3 showing the members in another position. Fig. 7 is an enlarged vertical sectional view on the line 7—7 of Fig. 2. Fig. 8 is an enlarged vertical transverse sectional view on the line 8—8 of Fig. 1.

Referring particularly to the accompanying drawings, 10 represents the main track and 11 the branch or siding. Secured to 50 the tie 12 is a plate 13 on which are pivotally mounted the combined switch points and guard rails 14 and 15, the former being adapted for use in connection with the main line while the latter is used for the curve 55 of the branch. Disposed transversely under the rails is a slid able bar 16 provided with

a pair of vertically extending pins 17 which engage in longitudinally arranged grooves 18 in the lower or base portion of the outer ends of the switch points 14 and 15. Dis- 60 posed between the main track and the siding is a suitable stand 18', the upper portion of which has mounted therein a short trans- verse shaft 19 carrying a large pinion 20.

On the opposite ends respectively of the 65 shaft 19, and outwardly of the stand are the star wheels 21 and 22. In the lower portion of the stand is mounted one end of a shaft 23, this shaft extending under the main track to a second smaller stand or housing 24. On 70 the end of the shaft within the stand 18 is a pinion 25 which meshes with a pinion 20 while on the end of the shaft which is dis- posed within the housing 24 is a pinion 26 meshing with a pinion 27 carried by a trans- 75 verse shaft 28 mounted in said housing. On the ends of the shaft 28 are mounted the crank disks 29 and 30, the former of which stands in a horizontal plane when the switch is thrown for the main line, while the other 80 crank disk stands in a vertical position.

Mounted on the outer end of the tie 31 is a bell crank lever 32 and pivotally connected to one arm of this lever and to the disk 29 by the wrist pin 33 is a link or rod 34. 85 Connected to the other disk 30 by means of the wrist pin 35 is a link or rod 36. The other end of this rod 36 is pivotally connected to one end of a bar 37 disposed trans- versely under the main track adjacent the 90 switch, and pivoted centrally between the rails of the main track as indicated at 38. Disposed on the same side of the main line but at the other end of the switch is a stand 18'' having mounted therein the shaft 95 19', this shaft carrying a pinion 20' within the stand and a star wheel 21' outwardly of the stand. This stand is also provided with the shaft 23' and pinion 25', this latter pin- 100 ion meshing with the pinion 20'. The op- posite ends of the shaft 23' carry crank disks 39 and 40 respectively, the former be- ing connected to the other end of the rod 37 by means of the link 41, while the disk 40 is connected to one end of a bell crank lever 42 by means of a link 43. The other arm of the bell crank is loosely connected with the bar 16 as indicated at 44.

Mounted on a suitable block adjacent the bar 16, and outwardly of the curve of the 110 siding is a post 45, the upper end of which carries a transversely extending member 46

provided with a vertical notch 47. A resilient lever 48 is pivotally mounted on the lower end of the post 45 and has its upper end normally held within the notch 47. Pivotally connected at its opposite ends to the lever 48 and to the adjacent end of the bar 37 is a link 49. Pivotally mounted adjacent the post 45 is a hand lever 50, one end of which is loosely connected with the bar 16 at 51. This bar 16 extends under a signal stand 52 and is pivotally connected to a crank disk 53 by means of a link 54, the said crank disk being mounted on the lower end of the signal post 55. The upper end of the post carries the usual clear and danger target blades 56 and 57.

Mounted on the pilot of the locomotive 58 is a transversely slidable rod 59, this rod having pivotally connected intermediate its ends one arm of a bell crank lever 60, this crank having its other arm connected to an operating lever in the cab by means of a connecting rod or link 61. This rod is mounted in brackets 62 carried by the pilot. This rod 59 when projected from either side of the locomotive is adapted to engage with one of the star wheels 21 or 21' to rotate the same, as will be readily understood.

The gear 25 and the gear on the shaft 28 are so proportioned with respect to the gears 20 and 26, and the gear 25' so proportioned with respect to the gear 20' that a one-fifth revolution of the gears 20 and 20' will cause a one-half revolution of the gears 28 and 29 and shift the cranks 29 and 40 to points diametrically opposite to those at their initial or starting positions. The said crank disks will then assume positions on a dead center.

Assuming that the switch to the main line has been left open as shown in Fig. 5, and that a train is moving in the direction shown in Fig. 1, when the wheels of the locomotive struck the open switch, it might be derailed. To obviate this danger, the operating lever is moved to shift the rod 59 so as to project from the left side of the pilot. This projecting end will engage the star wheel 21, turn the same which will communicate motion to the shaft 28 through the gearing in the stands 18' and housing 24. It will be noted that the crank disk 29 is on a dead center, and by this rotation of the shaft 23 the crank disk will be moved off center so as to actuate the rods or links 34 and 36. The rod 34 will rock the bell crank lever 32, shifting the bar 16 toward the signal stand and move the switch point 14 in line with the main track and the point 15 away from the main track. The rod or link 36 at the same time rocks the lever or rod 37 on its pivot 38, moving the crank disk 39 and rotating the shaft 23'. The bell crank 42 is rocked by the movement of the bar 16 when the shaft 23' is rotated far

enough to move the disk 40 off dead center. When the rod 37 is rocked on its pivot, the link 49 will pull the lever 48 out of the notch 47. Should it be desired to return the switch to original position after the train 70 has passed along the main line, the rod 59 is left in projected position so that it will engage the star wheel 21'. This will operate through the pinions 20', 25' and links 41 and 43 to slide the bar 16 back into original 75 position.

Elements similar to those marked 59 and 60 are mounted on the last car of the train. This will be clearly understood, and it is not thought necessary to illustrate the same. 80

Should a train be coming from the siding toward the main line, the rod 59 would be projected with the opposite side of the pilot so as to engage with the star wheel 22 on the other side of the stand. 85

To operate the switch by hand, it is necessary to move the lever 48 out of its notch for the purpose of moving the crank disks 29 and 40 off center. This will automatically occur when the star wheels are engaged by the rod 59, but it is impossible to turn the star wheels by hand to actuate the switch, the lever 48 being sufficiently strong to resist movement when an attempt is made to turn the star wheel. When the lever 48 95 is moved out of the notch 47, the lever 37 will be rocked on its pivot, whereby the links 36 and 41 will move the cranks 30 and 39 a sufficient distance to shift the cranks 40 and 29 off center. This accomplished, the 100 switchman can grasp the lever 50 and actuate the bar 16 to throw the switch points, and complete the rotation of the cranks, 40, 29, 39, and 30. It will be noted that the operation of the lever 48 simply moves the 105 cranks 40, and 29 through an angle of approximately 90°, which correspondingly moves the entire mechanism, but the remainder of the operation of the mechanism is accomplished by the throwing of the lever 50. This is useful in shifting cars onto a siding or a branch line. 110

What is claimed is:

1. In an automatic railway switch, a main line and a branch, a switch, train actuated 115 tappets arranged at suitable distances from the ends of the switch for operating the switch, a manual means for operating the switch including a releasable holding means connected with the tappet, said holding 120 means being capable of movement manually to impart an initial movement to the tappet.

2. In an automatic railway switch, a main line and a branch, a transversely movable member between the main line and the branch, switch points mounted between the main line and the branch and movably connected with the transversely movable member, a rotatable train actuated tappet mounted at one side of the main line and includ- 130

ing gears and cranks, means for holding the one of said cranks on dead center, said means being capable of automatic release by the train actuated means, but incapable of 5 manual release from the train actuated means, and manual means for operating the switch capable of movement only when the

locking means is directly actuated manually. In testimony whereof I affix my signature, in the presence of two witnesses.

FOSTER L. HARMON.
